CLAIM

The ornamental design for a golf tee, as shown and described.

DESCRIPTION

FIG. 1 is a perspective view of the golf tee showing a first embodiment of our new design.

FIG. 2 is front view of FIG. 1.

FIG. 3 is side view of FIG. 1.

FIG. 4 is bottom view of FIG. 1.

FIG. 5 is a perspective view showing a second embodiment of our new design.

FIG. 6 is front view of FIG. 5.

FIG. 7 is side view of FIG. 5; and,

FIG. 8 is bottom view of FIG. 5.

The broken lines are included for the purpose of illustrating portions of the golf tee that form no part of the claimed design.
